(57) CLAIM

The ornamental design for a cosmetic container, as shown and described.

DESCRIPTION

FIG. 1 is a front, top, and right side perspective view of a cosmetic container showing my new design.

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear, bottom, and right side perspective view thereof.

The design is of a cosmetic container intended for use as a cosmetic container.

The text "XUYONI" forming part of the claimed design is a registered trademark of Ju Yeon Pae.
